UNITED STATES PATENT OFFICE

ALVONI A. WOODS, OF CHICAGO, ILLINOIS, ASSIGNOR TO ALL-AMERICAN MOHAWK CORPORATION, OF CHICAGO, ILLINOIS, A CORPORATION OF ILLINOIS

RADIOCONTROL

Application filed May 31, 1929. Serial No. 367,226.

This invention relates to control devices for radio receiving sets, and has for its principal object to provide a single control knob which may be selectively used for several purposes, as for instance, for tuning, volume and current control.

In carrying out my invention, I provide a control knob which is arranged to operate certain of the control devices, as for instance, the volume and current controls, by rotation of said knob, but which may also, by swinging the knob laterally, serve to control other devices, as for instance, the tuning condensers or similar tuning devices. In this manner, both the volume and current can be controlled in any position of the tuning adjustment.

The invention may best be understood by reference to the accompanying drawing, in which

Figure 1 is a side view of a device constructed in accordance with my invention, as applied to a panel and sub-panel of a radio receiving set.

Figure 2 is a plan view of the device shown in Figure 1.

Referring to details of the mechanism illustrated in the drawing, my invention is shown as applied to a radio receiving set of any suitable construction, which, for instance, may have a front panel 10 and a base 11 connected therewith. The single control device comprises a rotatable knob 12 projecting through a slot 13 herein extending horizontally in front of the panel 10 in a position to be manipulated by hand.

In the embodiment of my invention herein illustrated, the knob 12 is mounted on a shaft 14 journaled in upright supports 17, 17 carried on a bracket 18. This bracket is mounted on the base 11 to swing in a horizontal plane and for this purpose being suitably pivoted, as for instance, on a pin 16 on said base. Control cables 19, 19 are suitably attached to the bracket 18 and extend to the tuning element of the set which may be the cable drum of the condenser shaft, or the like, (not shown) so as to rotate the tuning element by a horizontally swinging movement of the entire bracket 18 and parts carried thereby.

This swinging movement of the bracket, of course, is under manual control of the operator through manipulation of the knob 12 extending through slot 13 in front of the panel.

A volume control device 24 is mounted on a support 25 also carried by the bracket 18, said device herein shown being of any well known form of resistance element controlled by rotation of the shaft 14. Said shaft also extends through the resistance element 24 and is provided at its end with a crank arm 27 which carries a dog 28. This dog is arranged to cooperate with a tumbler element 30 of tumbler switch 31 of standard construction, suitably mounted on the bracket 18 as shown. Said tumbler switch is preferably adapted to control the main operating circuits of the receiving set, although it may be used to control other elements as, for instance, loud speaker connections, or the like.

From the above description it will now be understood that the single control knob 12 may be rotated to control the volume or to turn the main circuit connections on or off as desired. At the same time the set may be tuned by swinging the control knob horizontally. The volume and circuit controls may be operated at any point of tuning adjustment, so that the latter need not be disturbed when controlling the volume at any given station, or for leaving the set tuned to said station when it is turned off.

Although I have shown and described one embodiment of my invention, it will be understood that I do not wish to be limited to the exact construction shown and described, but that various changes and modifications may be made without departing from the spirit and scope of my invention.

I claim:

1. In a radio receiver, a base, a supporting member pivotally mounted on said base, control means mounted on said supporting member, an actuating knob for said control means rotatable on an axis extending transversely of the pivotal axis of said supporting member, and other control means operatively connected with said supporting member and actuated by pivotal swinging movement of

said member effected through manual control of said knob.

2. In a radio receiver, a base, a supporting member pivotally mounted on said base, electric control means mounted on said supporting member, an actuating knob for said control means rotatable on an axis extending transversely of the pivotal axis of said supporting member, and tuning control means operatively connected with said supporting member and actuated by pivotal swinging movement of said member effected through manual control of said knob.

3. In a radio receiver, a panel having a slot therein, a supporting member pivotally mounted on an axis disposed to the rear of said panel and extending transversely of said slot, a rotatable coaxial member carried on said supporting member and extending through said slot in position to be manually adjusted either by axial rotation or shifting movement in said slot, and two control devices, one actuated by rotation of said control member and the other actuated by pivotal swinging movement of said supporting member.

Signed at Chicago, Ill. this 27 day of May, 1929.

ALVONI A. WOODS.
